UNITED STATES PATENT OFFICE

137,470

DESIGN FOR A COMBINED WALLET AND CASE FOR KEYS AND SIMILAR ITEMS

Siegbert Wetterhahn, New York, N. Y.

Application December 21, 1943, Serial No. 112,068

Term of patent 7 years

To all whom it may concern:

Be it known that I, Siegbert Wetterhahn, a citizen of no country, residing at the city of New York, in the county of New York and State of New York, have invented a new, original, and ornamental Design for a Combined Wallet and Case for Keys and Similar Items, of which the following is a specification, reference being had to the accompanying drawings, forming part thereof.

In the drawing:

Figure 1 is a perspective view of a combined wallet and case for keys and similar items show-

ing my new design, billfold section of the wallet being opened and case being closed.

Figure 2 is a perspective view thereof showing the case for keys and similar items in open position, and

Figure 3 is a perspective view thereof showing the complete article in its closed and folded position.

I claim:

The ornamental design for a combined wallet and case for keys and similar items.

SIEGBERT WETTERHAHN.
